(57) **CLAIM**

The ornamental design for a slot pattern for EMI/RFI shield, as shown and described.

DESCRIPTION

FIG. 1 is a perspective view of the slot pattern for EMI/RFI shield showing my new design disposed, by way of example only, across a generally curved surface portion of an exemplary EMI/RFI shield;

FIG. 2 is a top plan view of the slot pattern for EMI/RFI shield shown in FIG. 1; and,

FIG. 3 is a bottom plan view of the slot pattern for EMI/RFI shield shown in FIG. 1.

The details shown in broken lines are for illustrative purposes only and form no part of the claimed design.
